UNITED STATES PATENT OFFICE.

FRANZ F. NICKEL, OF EAST ORANGE, NEW JERSEY, ASSIGNOR TO HENRY R. WORTHINGTON,
A CORPORATION OF NEW JERSEY.

TUBE-HEAD.

No. 887,113.

Specification of Letters Patent.

Patented May 12, 1908.

Application filed June 11, 1907. Serial No. 378,361.

To all whom it may concern:

Be it known that I, FRANZ F. NICKEL, a citizen of the United States, residing at East Orange, county of Essex, and State of New Jersey, have invented certain new and useful Improvements in Tube-Heads, fully described and represented in the following specification and the accompanying drawings, forming a part of the same.

10 The object of the present invention is to provide an improved tube head for surface condensers, coolers, and the like, where two fluids are to be separated, and it is desired to avoid leakage from one to the other.

15 The invention is especially intended for use in oil coolers, where the oil and cooling water are to be separated, or surface condensers where salt condensing water and the boiler water condensed from the steam are to 20 be separated, but is applicable also in many similar uses.

The invention consists in a tube head made in two parts with space between them, into which space any leakage through the 25 packing in either head passes, so as not to pass through both heads from one chamber to the other.

In the accompanying drawings forming a part of this specification, I have shown the 30 invention as applied to a common type of condenser or cooler, and this construction will now be described in detail, and the features forming the invention specifically pointed out in the claims.

35 In the drawings—Figure 1 is a vertical section of one end of the condenser or cooler. Fig. 2 is an enlarged sectional detail of a portion of the tube head.

Referring to the drawings, A is the condenser shell inclosing the tubes, B the chamber with which the tubes connect, C the tubes, and D the tube head in which the tubes are secured so as to open to chamber B.

The tube head D consists of two plates 10, 40 11, which are shown as held apart by disks 12 on bolts 13 by which the parts A, B, D, are clamped together, but which plates 10, 11, may be held separated in any other suitable manner to form a space 14 between them. The tubes C pass through the plates 50 10, 11, and are packed therein, suitable pack-

ings 1, with the screw packing sleeves 2, 3 for the respective plates 10, 11, being shown. The packing sleeve 2 is provided with openings 4 opposite the space 14 so that any 55 leakage through the packings and between the sleeve 2 and tube C will pass out to the space 14.

It will be understood that the condenser shown is selected only for the purpose of 60 illustration and is one type of many structures with which the invention is applicable, and that the invention is not to be limited to the detailed form or arrangement of the tube head or packings shown, but that these may 65 be modified widely while retaining the invention defined by the claims.

What I claim is:—

1. A tube head formed in two parts through which the tubes pass and in each of 70 which parts the tubes are packed, the space between said parts being open to the tubes for receiving leakage between the tubes and packing.

2. The combination with a chamber, of a 75 tube passing through the chamber, and a head closing the chamber in which the tube is packed, said head consisting of two parts in each of which the tube is packed with a space between them open to the tube for receiving leakage between the tube and the packing.

3. The combination with two chambers, of tubes passing through one chamber and opening to the other chamber, and a tube 85 head in which the tubes are packed, said tube head being formed of two plates with space between them open to the tubes for receiving leakage between the packing and tubes.

4. The combination with tube C, of tube 90 head D formed of two plates 10, 11, with space between them, and packing for the tube in said heads with openings 3 through the packing sleeve connecting with the space between the plates.

In testimony whereof, I have hereunto set my hand, in the presence of two subscribing witnesses.

FRANZ F. NICKEL.
